UNITED STATES PATENT OFFICE

HENRY JOSEPHS, OF NEW YORK, N. Y.

DESIGN FOR A SHOE HORN

Application filed December 3, 1932. Serial No. 46,297. Term of patent 7 years.

To all whom it may concern:

Be it known that I, HENRY JOSEPHS, a citizen of the United States, residing in New York city, in the county of Bronx and State of New York, have invented a new, original, and ornamental Design for Shoe Horn, of which the following is a specification, reference being had to the accompanying drawing, forming part thereof.

Figure 1 is a plan or face edge of a shoe horn embodying my new design;

Figure 2 is a front edge view of the same; and

Figure 3 is a longitudinal sectional view shown as taken on the line 3—3 of Figure 1.

I claim:

The ornamental design for a shoe horn, substantially as shown.

HENRY JOSEPHS.
